UNITED STATES PATENT OFFICE.

WILLIAM F. PRICE, OF GLASTONBURY, CONNECTICUT.

DISPLAY STAND.

Application filed August 24, 1927. Serial No. 215,239.

This invention relates to a display stand for holding articles of sale, such as sacks of potato chips, and also adapted to carry advertising matter relative to the wares for sale.

The aim of the invention is to provide a simple, durable and economic device of this sort by means of which the wares may be effectively displayed in such manner that they may be readily and expeditiously withdrawn and taken from the device when a purchase is made. My improved arrangement is such that the articles for sale may be readily strung onto a spindle and expeditiously withdrawn therefrom, the pointed end of the spindle being at all times protected so that no one can injure themselves thereon, and means being provided for advantageously displaying one or more articles of advertising.

Other objects will be in part obvious and in part pointed out more in detail hereinafter.

The invention accordingly consists in the features of construction, combination of elements and arrangement of parts which will be exemplified in the construction herein-after set forth and the scope of the application of which will be indicated in the appended claims.

In the present instance, I have referred to my device in connection with its use for displaying sacks of potato chips but, obviously, it may be employed to display wares of various kinds and particularly articles which may be strung onto a vertical needle or spindle.

In the accompanying drawings, wherein I have shown, for illustrative purposes, one of the many embodiments which the present invention may take:

Figure 1 is a perspective view of my device;

Fig. 2 is a sectional view taken substantially on line 2—2 of Fig. 1; and

Fig. 3 is a perspective view showing the free end of the cross bar and the upper end of one of the standards with which the cross bar is adapted to interlock when the latter is in normal position.

Referring to the drawings in detail, the device has a base which may be variously constructed but which is here shown as comprising a ring or hoop 10 provided with a diametrical strut 11. Arising from the center of the diametrical strut is a relatively

long needle or spindle 12, the upper end of which is pointed as at 13 in order that the articles to be displayed may be easily punctured by the needle when threading the articles thereon. Arising from opposite sides of the ring are upright strips or standards 15 and 16 which are preferably made of metal. The upper end of the standard 15 is bent over upon itself so as to provide a double thickness and this upper end is slotted so as to provide three fingers 17 with notches therebetween. The upper end of the standard 16 is notched as at 18 so as to provide three fingers 19 similar in position to the fingers 17.

Supported on the upper ends of the standards 15 and 16 is a guard and advertising carrying element A which is in the form of a channel-shaped cross bar. This element may be formed of an integral channel-shaped member or of more than one part, in the present instance it being shown as having two side or web members 20 and a bottom or connecting member 21 suitably connected together as by means of welding or pins.

One end of this element has ears 22 adapted to fit in the notches between the fingers 17 of the standard 15. For the purpose of hinging the element to the standard 15, a pin or pintle 23 extends transversely through the fingers 17 and the ears 22. The free or left hand ends of the webs 20 are adapted to fit in the notches 18 of the standard 16 when the element is in normal position, and thus the element is held against lateral play.

In order to suitably tie the upper ends of the standards 15 and 16 together, the webs 20 are notched, as at 24, adjacent their free ends so that they may receive the edges at the inner ends of the notches 18. The groove or channel 25 in the upper face of the element is adapted to receive suitable advertising matter, such as a card, praising the wares on display, the card being shown in dotted lines in Figs. 1 and 2.

The element A carries a guard which is slidably mounted for vertical movement under its own weight. In the present instance, this guard, designated generally by the letter B, is U-shaped in cross section, as shown in Fig. 2. It has a pair of arms 30 adapted to straddle the element A and a block 31 provided with a pocket or recess 32 adapted to receive the pointed end of the spindle 12 when the parts are in normal position. While the guard B is shown in

the present instance as being formed of three parts, obviously it can be formed of any number of parts. The opposite sides of the element A are provided with guide members 33 suitably secured in place as by means of welding or the like. These guide members form, with the element A, openings which slidably receive the arms 30 of the guard. In order to prevent the guard from dropping 10 out of place, the upper edges of the arms are provided with projections 35. The manner in which the device is used is clear from the drawings. When it is desired to thread the articles of sale, such as 15 sacks of potato chips on the needle 12, the element A is thrown up so as to remove any obstruction at the upper end of the needle. After the articles have been threaded onto the needle, the element A is thrown down to 20 the position shown in Fig. 1 and in which position the free end of the element A is interlocked with the standard 16. The guard, owing to gravity, takes its lowermost position and in this position covers the point 25 of the needle 12. Advertising matter, such as a card, is adapted to have its lower edge inserted in the channel of the element A. When a purchase is made, the uppermost 30 article is moved to the top of the needle and against the guard which is thus raised so that the article can be withdrawn from the needle.

As many changes could be made in the 35 above construction and many apparently widely different embodiments of this invention could be made without departing from the scope thereof, it is intended that all matter contained in the above description or shown in the accompanying drawing shall 40 be interpreted as illustrative and not in a limiting sense.

It is also to be understood that the language used in the following claims is intended to cover all of the generic and specific 45 features of the invention herein described and all statements of the scope of the invention which, as a matter of language, might be said to fall therebetween.

I claim as my invention:

1. A display device having a base, a spindle extending upwardly therefrom and on which articles of sale are adapted to be threaded, a movable element extending over the top of said spindle, and a gravity guard 55 mounted for vertical sliding movement on said element and adapted to protect the upper end of said spindle.

2. A display device having a base, a spindle extending upwardly therefrom, a hinged element above and extending transversely of 60 said spindle and having means for supporting advertising matter, and a guard carried by said element, said guard having vertical sliding movement and being normally urged downwardly by gravity. 65

3. A display device having a base, a spindle extending upwardly therefrom, an element extending transversely of and positioned above said spindle, said element having a groove adapted to receive advertising 70 matter, and a guard slidably carried by said element for covering the upper end of said spindle.

4. A display device having a base, a spindle extending upwardly therefrom, a channel-shaped element extending transversely of and above said spindle, said element being mounted for movement to and from normal position over said spindle, and a guard member straddling said element and having 75 vertical sliding movement. 80

5. A display device having a base, a spindle extending upwardly therefrom, an element extending transversely of and positioned above said spindle, means carried by 85 said base for supporting said element, and a guard member carried by said element, said guard member being vertically movable in the line of said spindle. 90

6. A display device having a base, a spindle extending upwardly therefrom, a pair of standards extending upwardly from said base, an element supported on the upper ends of said standards and tying the same together, and a guard for said spindle carried by said element. 95

7. A display device having a base, a spindle extending upwardly therefrom, a pair of standards extending upwardly from said base, an element supported on and tying together the tops of said standards, said element having a groove in its upper surface to receive advertising matter, and a guard for said spindle carried by said element. 100

8. A display device having a base, a spindle extending upwardly therefrom, a pair of standards extending upwardly from said base, an element hinged to one of said standards, cooperating means between the other end of said element and the top of the other standard for locking said parts together, and a guard for said spindle carried by said element. 110
